UNITED STATES PATENT OFFICE.

DIX D. DRAKE, OF BUFFALO, NEW YORK.

MORTAR-GAGE.

1,241,611.

Specification of Letters Patent.

Patented Oct. 2, 1917.

Application filed April 5, 1916. Serial No. 89,106.

To all whom it may concern:

Be it known that I, Dix D. DRAKE, a citizen of the United States, residing at Buffalo, in the county of Erie and State of New York, have invented new and useful Improvements in Mortar-Gages, of which the following is a specification.

This invention relates to a mortar-gage which is more particularly designed for use by bricklayers in order to enable the same to obtain the desired thickness of successive layers of mortar between superposed layers of brick without depending upon the eye or guess work for this purpose, thereby not only expediting the laying of bricks but also securing greater uniformity or evenness in the laying of the different courses of brick. While this device is more particularly designed for use in connection with the laying of bricks, the same may also be used to good advantage in laying tile, concrete blocks, building stone and the like in which similar conditions exist.

It is the purpose of this invention to provide a mortar-gage for use in laying bricks, or the like, which is simple in construction, convenient in use and so designed that it facilitates the laying of bricks in an even and uniform manner.

In the accompanying drawings: Figure 1 is a perspective view of one form of mortar-gage which embodies my invention. Fig. 2 is an end elevation of the same, showing the mortar-gage applied to a wall which is being erected. Fig. 3 is a bottom plan view of the gage. Figs. 4 and 5 are detached perspective views of one section of the coupling and one section of the hanging device forming part of my improved mortar-gage.

Similar characters of reference indicate corresponding parts throughout the several views.

In its general construction, this mortar-gage comprises a gage-bar which is adapted to be arranged adjacent to the upper outer corner or corners of one or more bricks 19 in the uppermost course which has just been laid, a hanging device adapted to be supported by the top layer of bricks, a coupling device for connecting the hanging device and the gage-bar, and a handle whereby the gage may be manipulated.

Although the gage-bar may be made of any suitable material and of various forms to suit the particular character of the work in hand, it is preferable for the sake of

lightness and economy, to construct the gage-bar of a body 1 of wood and to provide the same on its inner longitudinal edge with a facing strip 2 of metal which may be secured thereto by means of screws 3, as shown in Fig. 1, or by any other suitable means. This gage-bar is adapted to be supported with its facing strip adjacent to the upper outer corner of a course of bricks in such position that the top of this bar is arranged a distance above the upper side of the top course of bricks corresponding to the thickness of the layer of mortar which is to be placed between this course of bricks and the next course which is to be placed thereon. When the gage-bar is thus supported it is only necessary to apply the mortar 20 to the top of the last course of bricks and against the inner edge of the gage-bar and then strike off the top of the mortar even with the top of the gage-bar, when this mortar layer will be of the proper height or thickness to receive the next course of bricks without requiring any special tamping, adjustment or other manipulation of the bricks in order to bring them to the proper position relative to the next lower course of bricks.

In order to permit the gage-bar to be used for laying mortar in various thicknesses without making the gage-bar unduly thick, the body of the same is made comparatively thin, as shown in Figs. 1 and 2, and the facing strip on the front edge thereof is extended from the top of the body downwardly below the underside thereof to such an extent as will be suitable for laying the various thicknesses of mortar which are commonly employed for laying different kinds of brick, stone work, etc.

The hanging or suspension device whereby the gage-bar is supported in proper position on a course of brick or the like, preparatory to placing a layer of mortar on the top thereof, may be variously constructed but the form shown in the drawings comprises two hangers each having an upright supporting arm 4 which is adapted to engage with the outer side of the brick and provided at its upper end with an inwardly-projecting horizontal supporting-finger or lug 5 adapted to rest upon the upper side of a brick adjacent to its upper outer corner. These hangers are connected with the gage-bar by means which permit of adjusting the gage-bar vertically thereon and also horizontally relatively thereto. This adjustment may

also be effected by various means but those shown in the drawings are suitable for this purpose and comprise two L-shaped couplings each of which is provided with a 5 lower inner vertical leg 6 which is secured to the arm of one of the hangers on the outer side of the latter and an upper horizontal outwardly-projecting leg 7 which is secured to the underside of the gage-bar. The adjustable connection between the lower leg of 10 each coupling and the arm of the respective hanger preferably consists of a horizontal bolt 8 passing through a vertical slot 9 in said lower leg and one of a plurality of 15 openings 10 arranged in a vertical row in said arm, the head of this bolt bearing against the inner side of this arm and the nut thereof bearing against the outer side of the companion leg. By shifting this bolt 20 in the vertical slot of the companion coupling, a certain range of adjustment is obtained and by shifting the same from one opening 10 of the hanger arm to another this adjustment may be further increased to suit 25 the thickness of mortar for which the gage is to be used. In order to hold the hanger-arm and the lower leg of the companion coupling in proper position relatively to each other while the upper parts thereof are separated 30 by the lower edge of the gage-bar facing strip, a washer 11 or other spacing element is mounted on the bolt 8 between the lower leg of the respective coupling and the arm of the companion hanger, as shown 35 in Fig. 2. The horizontal adjustment of the gage-bar relative to the couplings is effected by means of a vertical clamping bolt 12 passing vertically through the body of the gage-bar and through a horizontal 40 slot 13 formed in the upper leg of one of the couplings. By shifting this bolt horizontally in the slot 13, the position of the gage-bar relatively to the front side of the course of bricks may be varied. When the 45 gage-bar is adjusted horizontally on the couplings, washers 11 of appropriate thickness are used between the couplings and the hangers to suit the position of the gage-bar.

By thus rendering the gage-bar adjustable horizontally, more or less of the mortar of each course may be permitted to project beyond the outer side or face of the bricks which projecting portion is usually "struck" 50 so as to present a convex appearance, as shown at 14 in Fig. 2, or the same may be otherwise treated to suit the particular character of the work in hand. In order to conveniently "strike" the projecting edge of the mortar, the outer longitudinal edge of 55 the gage-bar may be used for this purpose. For instance, as shown in Fig. 3, a strip of metal 15 is secured to the outer longitudinal edge of the gage-bar and provided on its outer side with a concave face 16 which 60 upon being run over the projecting edge of

the layer of mortar will impart a convex shape to the same, as shown at 14 in Fig. 2. By changing the outer face of the striking strip 15 on the gage-bar, any desired shape 70 may be given to the edge of the mortar.

If desired, the gage-bar may be so mounted 75 on the bricks that a part thereof inwardly overhangs the upper inner corner of the course of bricks, in which case the layer of mortar applied to the bricks will not come to the outer side or face of the bricks but will stop short of this face, thereby producing what is known as a "rake" or "raked out" joint between adjacent courses of bricks 80 without necessitating any special raking out operation for this purpose, as has been necessary heretofore when producing a joint of this character.

This raked-out joint may be conveniently produced by simply reversing the gage-bar 85 on its supports, so that that edge thereof carrying the strip 15 will project inwardly over the top of the bricks the required distance.

For convenience in manipulating this tool, 90 a handle 17 is provided which is preferably constructed of wood and secured at its inner end to the central part of the underside of the body of the gage-bar by means of a clamping bolt 18. When the tool is in condition for use, the handle is clamped to the gage-bar so as to project laterally therefrom, as shown by full lines in Figs. 1, 2 and 3, but when the tool is not in use, the handle may be folded over the gage-bar, as shown by dotted lines in Fig. 3, in which position of the parts the tool is very compact and can be stowed away in a tool chest without taking up any unnecessary amount of room. 105

Owing to the simplicity of this mortar-gage, the same can be produced at comparatively low cost, it can be readily adjusted to suit different kinds of work and by its use a person having comparatively little skill in laying bricks can lay up a wall uniformly and evenly, so that the cost of laying bricks can be materially reduced by the use of this appliance. 110

I claim as my invention:

1. A mortar-gage for laying bricks, &c., comprising a horizontally extending gage-bar adapted to be arranged adjacent to the outer upper corner of a layer of bricks, and a hanging device adapted to rest on the upper side of said layer and to support said bar with the top of the latter at a distance above the top of said layer. 115

2. A mortar-gage for laying bricks, &c., comprising a horizontally extending gage-bar adapted to be arranged adjacent to the outer upper corner of a layer of bricks, a hanging device adapted to rest on the upper side of said layer and to support said bar with the top of the latter at a distance above 120

125

130

the top of said layer, and means for adjustably securing said bar vertically relatively to said hanging device.

3. A mortar-gage for laying bricks, &c., comprising a gage-bar adapted to be arranged adjacent to the outer upper corner of a layer of bricks, a hanging device adapted to rest on the upper side of said layer and to support said bar with the top of the latter at a distance above the top of said layer, and means for adjustably securing said bar horizontally relatively to said hanging device.

4. A mortar-gage for laying bricks, &c., comprising a gage-bar adapted to be arranged adjacent to the outer upper corner of a layer of bricks, a hanging device adapted to rest on the upper side of said layer and to support said bar with the top of the latter at a distance above the top of said layer, and means for adjustably securing said bar vertically and horizontally relatively to said hanging device.

5. A mortar-gage for laying bricks, &c., comprising a gage-bar adapted to be arranged with its front edge adjacent to the outer upper corner of a layer of bricks, a hanging device comprising two vertical arms adapted to engage the outer side of said layer and each provided at its upper end with a finger adapted to rest on top of said layer, two L-shaped couplings each having a vertical leg arranged adjacent to the rear side of one of said arms and a horizontal leg arranged adjacent to the underside of said bar, and bolts connecting the legs of said couplings with said bar and arms, respectively.

6. A mortar-gage for laying bricks, &c., comprising a gage-bar adapted to be arranged with its front edge adjacent to the outer upper corner of a layer of bricks, a hanging device comprising two vertical arms having openings and adapted to engage the outer side of said layer and each provided at its upper end with a finger adapted to rest on top of said layer, two L-

shaped couplings each having a vertical leg provided with a vertical slot and arranged adjacent to the rear side of one of said arms and a horizontal leg having a horizontal slot and arranged adjacent to the underside of said bar, and means for adjustably connecting said couplings with said hanging device comprising bolts passing through said vertical slots in said vertical legs and through said openings in said arms and bolts passing through said horizontal slots in the horizontal legs of said couplings and through said bar.

7. A mortar-gage for laying bricks, &c., comprising a gage-bar adapted to be arranged adjacent to the outer upper corner of a layer of bricks, a hanging device adapted to rest on the upper side of said layer and to support said bar with the top of the latter at a distance above the top of said layer, a handle, and means for adjustably connecting said handle and bar comprising a clamping bolt passing vertically through the inner end of said handle and the central part of said bar.

8. A mortar-gage for laying bricks, &c., comprising a gage-bar adapted to be arranged adjacent to the outer upper corner of a layer of bricks, a hanging device adapted to rest on the upper side of said layer and to support said bar with the top of the latter at a distance above the top of said layer, and a facing strip arranged on the front edge of said bar and having its lower edge projecting below the underside of said bar.

9. A mortar-gage for laying bricks, &c., comprising a gage-bar adapted to be arranged adjacent to the outer upper corner of a layer of bricks, a hanging device adapted to rest on the upper side of said layer and to support said bar with the top of the latter at a distance above the top of said layer, and a striking facing arranged on the front edge of said bar.
